UNITED STATES PATENT OFFICE.

RUSSELL B. BENNETT, OF WESTERVILLE, OHIO.

COMPOSITION POST OR ANALOGOUS STRUCTURE.

No. 829,940.

Specification of Letters Patent.

Patented Sept. 4, 1906.

Application filed December 12, 1905. Serial No. 291,467.

To all whom it may concern:

Be it known that I, RUSSELL B. BENNETT, a citizen of the United States, residing at Westerville, in the county of Franklin and State of Ohio, have invented certain new and useful Improvements in Composition Posts or Analogous Structures, of which the following is a specification.

My invention relates to fence-posts of that class in which the body of the post is formed or molded while in a plastic state of cement or similar adhesive substances with any suitable building material.

The object of my invention is to provide a composition body which will not only be of indestructible nature and take the place of wood for use in fence-posts, telegraph and telephone poles, railway-ties, or objects of kindred nature, but which will provide a homogeneous structure in which is incorporated an improved non-corrosive non-decaying composition differing in certain respects from the other elements of the post and into which staples, nails, or other fastening devices may be easily and securely driven.

Heretofore the method usually employed for fastening fence wires, boards, and the like to a cement post has been either by incorporating wood in some form or other into the post during the molding operation or by molding certain staple-receiving metal devices in one face of the post at predetermined intervals or by molding various other metallic shapes at definite intervals which project from the face of the post or by forming a post with perforations which necessarily result in weakening its structure.

The wood if placed in the post when dry will swell and crack the cement before the same hardens. If placed in the post while it (the wood) is wet, it will shrink away from the cement and furthermore will in time decay. The metal devices for receiving staples cannot be so spaced as to adapt themselves to the varying spaces of all the different makes of wire-fencing nor can any other projecting forms of metal. Again, these projecting parts are in the way when it is desired to handle, store, or ship the post, and when the post is being handled they are likely either to injure the post or become themselves broken off with the result that the post is imperfect when ultimately it is desired to use the same. The metal projections if they are molded into the post while the post is

damp will in time rust off just where they enter the post.

I am aware that prior to my invention it has been proposed to incorporate in composition railroad-ties, fence-posts, or analogous articles a plug or the like of some composition to receive the staple, nail, or spike, or similar fastening device; but in every instance of which I am aware these plugs have been composed of a material which is a heterogeneous substance with that of which the main portion or body of the post is composed and which therefore results in producing unnecessarily weak places in the post or tie body.

My present invention consists, in contradistinction to what has already been accomplished and proposed in posts or similar articles of plastic composition, of a post which is formed of cement or similar adhesive substances which will harden when set to form an indestructible body and which has incorporated in it at any predetermined point or place or plane or along any definite line a portion formed partly of cement or some adhesive material of which the remainder of the body is composed, such portion being impregnated to a predetermined extent with some non-adhesive substance which will render such place or portion sufficiently penetrable or porous to admit of a staple or any desired fastenings to be driven therein and which will at the same time form a homogeneous mass with the remainder of the body which will not weaken the said body and which, if desired, may be indistinguishable from the remainder of the body so that the latter will be to all appearances exactly the same composition throughout. In the last-named event if the penetrable portion does not show by a slightly-contrasting color from the remainder of the body it may be definitely located by indentation-marks made with any suitable tool.

For a full description of the invention and the merits thereof, and, also, to acquire a knowledge of the details of construction of the means for effecting the result, reference is to be had to the following description and accompanying drawings, in which—

Figure 1 is a perspective view illustrating one embodiment of my invention in a fence-post, portions of the fence being broken away. Fig. 2 is a vertical sectional view of the post illustrated in Fig. 1. Fig. 3 illus-

trates in detail one form of my improved penetrable composition ready to be embodied in the face of a post. Fig. 4 is a cross-sectional view of the side composition illustrated in Fig. 3. Fig. 5 is a detail view illustrating another form of the said penetrable composition. Fig. 6 is a horizontal sectional view of the post, showing the penetrable portion embodied therein and of the form illustrated in Fig. 5. Fig. 7 is a horizontal sectional view of the post illustrated in Figs. 1 and 2. Figs. 8, 9, and 10 are horizontal sectional views of posts, illustrating modifications, hereinafter specifically referred to.

Corresponding and like parts are referred to in the following description and indicated in all the views of the drawings by the same reference characters.

As regards my present invention the post proper may be of any size or construction, dependent upon its particular use and location, as long as it embodies a body 1 of cement or similar plastic composition, which will harden when set to produce a stone-like structure. The foot of the post may be provided with oppositely-disposed lugs 2, which may sustain the post and prevent its withdrawal or upheaval after earth has been tamped down around said lugs.

In the manufacture of the post the plastic composition, which is composed largely of cement or similar cementitious substances, has incorporated in it at any predetermined point or place or places or along any definite line or plane a penetrable portion, which also consists largely of cement or adhesive substances; but is to a predetermined extent impregnated with a mixture of ashes, cinders, or burnt clay or any non-adhesive substance. The cement of this penetrable portion will effect such a binding relation with the remainder of the post that the entire structure will present a homogeneous appearance and will present a substantially equal appearance on its surface throughout, although it may be slightly contrasting in color, so as to readily determine by a glance where the slightly penetrable portion or portions is or are located. It is to be understood then that the completed post embodies a portion which is like the remainder of the post, composed largely of cement, and yet is sufficiently impregnated with some porous or non-adhesive substance as to render such portion penetrable, while the remainder of the post is impenetrable.

By using the term "penetrable" I do not wish it to be understood that the composition of cement, ashes, and cinders, or the like, is so soft that it can be penetrated by slight force or pressure, in which case it might weaken the post structure; but I mean to convey the impression that the said composition may be penetrated by staples or other

fastening devices driven into it with sufficient force to accomplish this end. It is to be understood that the remainder of the post structure is impenetrable, as it is stone-like in nature and will crack and break if an attempt be made to drive a staple or similar fastening device into it. This penetrable composition, which is non-corrosive in character, may be incorporated in the post structure at different places or points along different lines or planes, as has been before suggested. As illustrated in Fig. 2, the said composition (designated 7) is located in a channel 8 in the face of the post, the said channel being completely filled with said composition. It is to be understood that the penetrable composition is incorporated in the post structure when the same is being molded and that it therefore forms an integral part thereof. The post is then smoothed off and allowed to harden, at which time staples 9 may be driven into the composition with a firmness that holds the fence-wires securely to the post. The composition 7 may be only a small portion of the post structure, as shown in Fig. 7, or in further modifications it may form one or more faces of the post, as shown in Figs. 8 and 9, or the said composition may form an entire body of the post in some predetermined plane or portion thereof, as illustrated in Fig. 10, or it may be placed in a small channel at the top of the post, into which a staple may be driven to fasten a barbed wire, or for any other purpose, as shown in Fig. 1.

Within the purview of my invention the penetrable composition may be incased within a foraminous or reticulate screen of wire-mesh 10, as illustrated in Fig. 3, it being pressed into the casing formed of such wire-mesh, the ends thereof being preferably bent back upon themselves. By the use of the wire-mesh casing the composite filling is uniform throughout and materially reinforces the post structure. It is of course to be understood that the penetrable composition 7 is not limited to the V-shaped cross-section shown in Fig. 4, but that it may be T-shaped, as shown in Figs. 5 and 6, or any other convenient form desired. As the wire-mesh casing 10 is intended to be embedded beneath the surface of the post structure, it is entirely covered with cement and is throughout prevented from rusting.

Preferably the penetrable filling or composition is placed in the post at the desired point or placed just deep enough to allow the staple or nail to be driven into the post, so that its ends will be bent against the impenetrable portion of the post structure, and thereby be clenched or turned back upon itself to form a hook construction, as shown in Fig. 2.

By my invention when the staple is removed the holes formed by the staples in the

penetrable portion may be refilled, if desired, with the said penetrable substance or composition and another staple may be readily driven into the same place and be held with 5 equal firmness and the post become as good as new.

From the foregoing description, in connection with the accompanying drawings, it will be seen that I have provided a cement or 10 similar post structure into which is incorporated a penetrable composition the constituent parts of which are cement or other similar adhesive substance, preferably the same as the remainder of the post structure, and 15 ashes, cinders, burnt clay, or some other similar non-adhesive and somewhat porous substances which will produce a homogeneous post structure of stone-like composition and formation, the major portion of 20 which is impenetrable and sufficiently hard, while at predetermined points or places it is sufficiently penetrable to permit staples, nails, or similar fastening devices to be driven therein.

25 While I have used throughout the specification and claims the term "non-adhesive," as applied to the cinders, ashes, or similar substances with which the cement is impregnated to form the penetrable portion of the 30 post-body, this term is not to be confounded with the concrete of which the remainder of the post-body is composed. It is of course to be understood that the concrete or impenetrable portion of the post-body is not composed of pure cement, but has incorporated with it a certain amount of sand or gravel, as 35 is customary with compositions of this nature; but it is also to be understood that the penetrable portion, while also formed partly of cement, and therefore of partly the same 40 composition of which the remainder of the post is composed, yet such penetrable portion is so impregnated with the ashes, cinders,

or similar substances "non-adhesive" in the sense that I have used the term, that it will 45 be readily susceptible to receiving the staples or similar fastening means.

Having thus described the invention, what is claimed as new is—

1. A plastic post comprising a body portion consisting of concrete including a predetermined amount of cement and having molded therewith while both are in a plastic condition, a fastening-receiving portion formed partly of concrete, but impregnated 55 with a sufficient amount of non-adhesive porous material to render it penetrable.

2. A post comprising a concrete body a predetermined portion of which is composed of a mixture or cement with sufficient ashes, 60 cinders, burnt clay or similar non-adhesive material to render said portion penetrable.

3. A composite post comprising a body of concrete, and a staple or similar fastening-receiving portion formed partially of the 65 same material as the body of the post and partially of a non-adhesive substance and a metal casing for said staple-receiving portion; the latter being molded into its casing and subsequently molded in the body of the 70 post.

4. A composite post, comprising a concrete body, a wire-mesh casing molded therein, and a penetrable portion filling said casing and composed partly of the same cementitious substance as the body of the post and partly of a non-adhesive substance, and incorporated in the body of the post while the latter and the said penetrable portion are in a 75 plastic condition.

In testimony whereof I affix my signature in presence of two witnesses.
